RAILWAY BRAKE GEAR SUPPORT

Harry M. Van Sweringen, Chicago, Ill., assignor
to Chicago Railway Equipment Company, Chi-
cago, Ill., a corporation of Illinois

Application June 5, 1942, Serial No. 445,891

6 Claims. (Cl. 188—210)

The invention relates to the support of railway brake gear, and more particularly to the provision of a safety device associated with the bolster of a railway truck to prevent the falling of the brake beam, and parts carried thereby, to the rail in the event of failure of the usual hanger which normally supports the beam.

Many devices have been proposed and used for this purpose, and one form of such device comprises a flexible member secured at its ends to the beams at opposite sides of the bolster and between its ends extending over the bolster as illustrated, for example, in Figure 3 of H. E. Anderson Patent 2,159,582, issued May 23, 1939. The effectiveness of such a device is dependent upon the distance between the top of the bolster and the portion of the device extending over the bolster, and this distance will vary according to the set taken by the bolster springs and also by the amount of wear of the brake beam hangers, pins and heads. When new trucks are equipped with this type of support, the above-mentioned conditions may be compensated for more readily than where supports of this type are ordered for application to old trucks which will vary substantially in the critical dimensions.

One object of the present invention is to facilitate the maintenance of the effective height of the support which, in the preferred form of the invention, means the maintenance of the desired clearance between the top of the bolster and the portion of the support above the bolster.

Since the device of the class described is ordinarily carried by the beams and extends upwardly therefrom with its upper end being unsupported, there is a tendency for the upper end to swing transversely of the truck, thereby bending the lower ends back and forth at their points of support and tending to weaken the connected elements, and it is a further object of the present invention to prevent this action and the resulting tendency.

Another object of the invention is to utilize the safety support to hold the beam against tilting about its longitudinal axis and to resist such tilting without flexing the support at the point of its attachment to the beam.

These and other detail objects of the invention as will appear below are attained by the structure illustrated in the accompanying drawing, in which—

Figure 1 is a section through the bolster of a four-wheeled truck taken longitudinally of the truck and showing the associated wheels, brake heads and hangers normally supporting the latter and the safety support which comprises the particularly novel feature of the present invention.

Figures 2 and 4 are detail vertical sections 60

taken on the corresponding section lines of Figure 1.

Figures 3 and 5 are detail horizontal sections taken on the corresponding section lines of Figure 1.

Figure 6 is a view in section corresponding to one side of Figure 1 but illustrating another form of the invention.

Figure 7 is a substantially vertical section 10 taken on the corresponding section line of Figure 6.

Figure 8 is a detail section of one corner of a bolster with another form of support mounted thereon.

15 The structure shown in Figure 1 comprises the usual wheels 1, bolster 2 and truss type brake beams, each comprising a compression member 3, a tension rod 4, a strut (not shown) and brake heads 5 which carry the renewable shoes 6 which engage the wheels when the brakes are applied. Normally the beams are pivotally supported by hangers 7 swinging from pins 8 seated in brackets 9 on the truck frame F on which the bolster is carried by springs S.

20 25 The safety support, which may also function as a guide in the normal support of the beams by hangers 7, comprises an inverted U-shaped member 10 with its base extending over the bolster and having the lower ends of its legs secured to the respective beams. Member 10 may be a cable or a chain and possesses sufficient flexibility to readily accommodate movement of the brake beams to and from the wheels as the brakes are applied and released, which movement may reach a maximum of from 2" to 2½" by each 30 35 brake beam between the slack position of the beam equipped with new shoes and the applied position of the beam when the shoes are worn.

To prevent flexing of the intermediate portion 40 of member 10, the same is provided with a substantially rigid pipe 11 or other stiffening means. Preferably U-shaped clips 12 secured to the bolster form guides for pipe 11 and prevent its swaying back and forth transversely of the truck, 45 and thereby avoid flexing of the lower ends of member 10 where they are connected to the beams.

The left hand end of member 10 is shown secured to the beam by a bracket 13, a block 14 and a U-bolt 15. Bracket 13 extends over tension rod 4 and under compression member 3, having a U-shaped portion to receive the latter. U-bolt 15 passes under tension rod 4 and through the adjacent portion of bracket 13 and through block 14, the assembly being maintained by nuts 16. One or more shims 17 and 18 may be inserted, as indicated, to vary the height of block 14 and the angular disposition of bracket 13. Member 10 is assembled with block 14 by upsetting 50 55 its end.

The right hand end of member 10 is secured to the beam by a bracket 19 corresponding to bracket 13 but having a central socket forming portion 20 slidably receiving the block 21, in which the upset end of member 10 is seated, and block 21 is adjustably positioned in bracket portion 20 by a pin 22 inserted through a selected one of the openings 23 in spaced flanges 24 depending from the block. Bracket 19 may be provided with shims as at 17 and 18.

The securing devices at the ends of member 10 provide for individual adjustment of the height of each beam. The entire support, and both beams, may be adjusted by the device at the top of the bolster which comprises a bar 25 slideable vertically between the flattened sides 26 of pipe 11 and held in adjusted position by a cotter 27 inserted through a selected one of the openings 28 in the bar, the upper portion of the bar having an annulus 29 or other suitable seat for the intermediate portion of the base of member 10.

A structure as described above provides for the use of a substantially flexible safety support for the beams and extending over the bolster and adjustable intermediate its ends to vary the relative heights of the bolster and brake beams above the rail. Or it may be adjusted at its connection to each beam for the same general purpose, the latter-mentioned adjustment being particularly desirable if the beam hangers support the two beams at different heights. The structure also provides for varying the inclination of the beams to the horizontal to prevent dragging of ends of the brake shoes on the wheels when the brakes are released. The structure will avoid undesirable flexing of the main supporting member 10 because of the play of the device transversely of the truck or because of the tilting of the beams on their hangers or the swinging of the hangers from their supports.

Figure 6 illustrates another arrangement for securing some of these advantages and comprises a bracket 30 secured to the side wall of the bolster 31, a bracket 32 secured to the compression member 33 and the tension rod 34 of the beam, and a flexible support member 35 with its upper end adjustably secured to bracket 30 by a pin 36 inserted through a selected one of the holes 37 in the bracket, the lower end of member 35 having its end upset in a disc 38 pivoted by a pin 39 between upstanding ears 40 on bracket 32. This construction provides for the pivoting of member 35 at both ends and avoids any undesirable flexing of member 35 where it is connected to the beam and to the bolster.

Figure 8 illustrates another arrangement in which the support member 41 corresponds to that shown in Figure 6 and may be similarly connected to the beam (not shown). The connection to the bolster 42 is by means of a bracket 43 having a vertically disposed threaded shank extending through a bracket 44 on the bolster and adjustably held at a desired height by a nut 45 and lock nut 46.

It will be understood that one or more of the features shown in Figure 1 may be used without necessarily including all of the features although, if desired, all of the features may be used together and may cooperate to obtain the maximum adjustment and stability of the support. The details of the adjustment and stabilizing features of the support may be varied without departing from the spirit of the invention,

and the exclusive use of those modifications coming within the scope of the claims is contemplated.

What is claimed is:

5. In a safety support for a railway truss type brake beam, an elongated flexible member having means at one end for connecting it to the brake beam and having means spaced from said end for coacting with a truck bolster to carry the member in the event of failure of the normal support for the beam, the means for connecting the member to the beam comprising a bracket arranged to extend between the compression and tension members of the beam and having an intermediate portion through which the end of the flexible member is slideable, there being pin and aperture elements in said member end and bracket portion for holding them in a selected one of desired assembly relations to vary the effective length of the support.

10. In a safety support for a railway truss type brake beam, an elongated flexible member having means at one end for connecting it to the brake beam and having means spaced from said end for coacting with a truck bolster to carry the member in the event of failure of the normal support for the beam, the means for connecting the member to the beam comprising a bracket arranged to extend between the compression and tension members of the beam and having an intermediate portion through which the end of the flexible member is slideable, there being pin and aperture elements in said member end and bracket portion for holding them in a selected one of desired assembly relations to vary the effective length of the support.

15. In a safety support for railway truck brake beams comprising an inverted U-shaped member with its base arranged to overlie a truck bolster and with beam engaging parts at the ends of its legs, there being a device near the middle of said base for simultaneously adjusting the effective length of the member legs.

20. In a safety support for a railway truck brake beams comprising an inverted U-shaped member with its base arranged to overlie a truck bolster and with beam engaging parts at the ends of its legs, there being a device near the middle of said base for simultaneously adjusting the effective length of the member legs.

25. In a safety support for a railway truck brake beams comprising an inverted U-shaped member with its base arranged to overlie a truck bolster and with beam engaging parts at the ends of its legs, there being a device near the middle of said base for simultaneously adjusting the effective length of the member legs.

30. In a safety support for a railway truck truss type brake beam, an elongated flexible member of inverted U-shape with means at its ends for attachment to respective brake beams, a rigid structure receiving the portion of said flexible member constituting the base of its U-shape, opposite sides of said structure having aligned openings, a portion of said member forming a loop projecting through one of said openings, a bar slideable through said openings and having a part projecting from the structure and engaging said loop and having a part adjustably secured to said structure to vary the effective length of the portions of the flexible member extending beyond the ends of said structure.

35. In a safety support for a railway truck truss type brake beam, a bracket with portions arranged for attachment respectively to the compression member and the tension member of the brake beam, and an elongated member connected to said bracket for suspending it to a truck part, there being means for varying the inclination of said member and bracket, and the corresponding portions of the brake beam to which the latter is applied, to control the tilting of the beam as the brake is applied to the truck wheels.

40. In a safety support for railway truck truss type brake beam, a bracket with portions arranged for attachment respectively to the compression member and the tension member of the brake beam, and an elongated member connected to said bracket for suspending it to a truck part, there being means for varying the inclination of said member and bracket, and the corresponding portions of the brake beam to which the latter is applied, to control the tilting of the beam as the brake is applied to the truck wheels.

45. In a safety support for railway truck truss type brake beam, a bracket with portions arranged for attachment respectively to the compression member and the tension member of the brake beam, and an elongated member connected to said bracket for suspending it to a truck part, there being means for varying the inclination of said member and bracket, and the corresponding portions of the brake beam to which the latter is applied, to control the tilting of the beam as the brake is applied to the truck wheels.

50. In a safety support for railway truck truss type brake beam, a bracket with portions arranged for attachment respectively to the compression member and the tension member of the brake beam, and an elongated member connected to said bracket for suspending it to a truck part, there being means for varying the inclination of said member and bracket, and the corresponding portions of the brake beam to which the latter is applied, to control the tilting of the beam as the brake is applied to the truck wheels.

55. In a safety support for railway truck truss type brake beam, a bracket with portions arranged for attachment respectively to the compression member and the tension member of the brake beam, and an elongated member connected to said bracket for suspending it to a truck part, there being means for varying the inclination of said member and bracket, and the corresponding portions of the brake beam to which the latter is applied, to control the tilting of the beam as the brake is applied to the truck wheels.

60. In a safety support for railway truck truss type brake beam, a bracket with portions arranged for attachment respectively to the compression member and the tension member of the brake beam, and an elongated member connected to said bracket for suspending it to a truck part, there being means for varying the inclination of said member and bracket, and the corresponding portions of the brake beam to which the latter is applied, to control the tilting of the beam as the brake is applied to the truck wheels.

65. In a safety support for railway truck truss type brake beam, a bracket with portions arranged for attachment respectively to the compression member and the tension member of the brake beam, and an elongated member connected to said bracket for suspending it to a truck part, there being means for varying the inclination of said member and bracket, and the corresponding portions of the brake beam to which the latter is applied, to control the tilting of the beam as the brake is applied to the truck wheels.

70. In a safety support for railway truck truss type brake beam, a bracket with portions arranged for attachment respectively to the compression member and the tension member of the brake beam, and an elongated member connected to said bracket for suspending it to a truck part, there being means for varying the inclination of said member and bracket, and the corresponding portions of the brake beam to which the latter is applied, to control the tilting of the beam as the brake is applied to the truck wheels.
